CLAIM

The ornamental design for a broom head, as shown and described.

DESCRIPTION

FIG. 1 is a perspective front view showing my new design of a broom head;

FIG. 2 is a front view thereof;

FIG. 3 is a rear view thereof;

FIG. 4 is a top view thereof;

FIG. 5 is a left side view thereof; and,

FIG. 6 is a right side view thereof.

The broken line showing in FIGS. 1–6 is for illustrative purposes only and forms no part of the claimed design.
